UNITED STATES PATENT OFFICE

2,570,553

APPARATUS FOR BLOWING OR PUMPING
OIL WELLS

John B. Hawley, Jr., Minneapolis, Minn.

Application December 6, 1945, Serial No. 633,158

15 Claims. (Cl. 103—234)

1

This invention relates to a method and apparatus for blowing an oil well or in other words discharging oil from the well by means of air under pressure.

In many cases where oil wells have been so blown, it has been necessary to fill the entire well or casing with compressed air. Such a method is wasteful of compressed air and the cost of compressing air becomes prohibitive. Another objection to previous methods of blowing or flowing a well is the fact that the face of the oil sand is subjected to high pressure which forces the oil back from the well into the sand. Furthermore if the oil sand has high permeability tremendous quantities of compressed air escape into the oil sand.

It is an object of this invention to provide a method and apparatus for blowing or flowing an oil well in which the compressed air is efficiently used and conserved.

It is a further object of the invention to provide a method and apparatus for flowing an oil well in which a casing of great length is used forming a collection chamber, the bottom of which chamber is disposed quite a distance below the bottom of the oil sand and into which chamber the oil flows by gravity together with a discharge pipe extending downwardly into said chamber to adjacent the bottom thereof with means for delivering compressed air into said casing and then subsequently delivering said air into a chamber about said casing and between the same and wall of the well.

It is a further object of the invention to provide an apparatus for flowing an oil well comprising a casing extending downwardly into the well below the oil sand and forming a chamber therein adapted to receive oil by gravity flow, a discharge pipe extending downwardly in said casing to adjacent the bottom thereof, means for delivering air under pressure to said casing, and means for determining the amount of oil in the well which is approximately the same level as the oil in said chamber of said casing.

It is another object of the invention to provide an apparatus for flowing an oil well comprising a casing extending downwardly into said well below the oil sand and having openings therein to receive oil by gravity flow, there being a chamber between said casing and the wall of said well, a discharge pipe extending downwardly into said casing to adjacent the bottom thereof, means for delivering compressed air to said casing for forcing oil through said discharge pipe, and means for delivering the compressed air in said

2

casing to the chamber between said casing and the wall of said well.

These and other objects and advantages of the invention will be fully set forth in the following description made in connection with the accompanying drawings in which like reference characters refer to similar parts throughout the several views and in which:

Fig. 1 is a partly schematic view showing the 10 well in vertical cross section and showing valve blocks used in vertical and horizontal cross section;

Fig. 2 is a view in vertical section of the lower portion of the well and parts therein;

Fig. 3 is a horizontal section taken on line 3—3 of Fig. 2, as indicated by the arrows;

Fig. 4 is a horizontal section taken on line 4—4 of Fig. 2, as indicated by the arrows, Figs. 3 and 4 being shown on an enlarged scale;

Fig. 5 is a view in front elevation of the valve blocks and parts carried thereby, parts of the well being shown in vertical section;

Fig. 6 is a top plan view of the valve blocks and parts carried thereby; and

Fig. 7 is a horizontal section taken on line 7—7 of Fig. 2, as indicated by the arrows.

Referring to the drawings, an oil well is shown having a chamber 10 in the upper part of which is disposed a casing 11. Casing 11 is connected at its upper end to a valve block 12 having a lower connecting portion 13. A casing 14, illustrated as of cylindrical form, is disposed in the well 10 and extends downwardly thereinto for quite a distance below the oil-bearing sand. While the size and length of said casing may be varied, in practice this casing has been made about four inches inside diameter and approximately three hundred feet long, the same having a capacity of approximately 4½ barrels of oil, said casing being lowered to adjacent the bottom of the collection chamber 10a in the well and it has been disposed with its bottom about 125 feet below the bottom of the oil-bearing sand. Casing 14 adjacent its lower end has sets of circumferentially spaced slots or openings 14a therethrough and the oil flows through these openings into the casing 14 until the oil level in the casing is substantially the same as the oil level in the well. As shown, casing 14 is spaced 40 from the wall of the well so that there is a chamber 10b between said casing and the wall of the well. As shown, casing 14 may comprise several sections which will be threaded and connected by the sleeves 14c. A discharge pipe 16 extends

50 downwardly inside of casing 14 to adjacent the 55

bottom thereof, said discharge pipe 16 having connected therein a sleeve 16a having a plurality of radially extending and circumferentially spaced holes 16b therethrough, said sleeve having a lower portion threaded into a valve cage 17 having a number of circumferentially spaced ribs 17a projecting inwardly from its wall and disposed above a valve seat 17b with which a ball valve 18 is adapted to cooperate. A screen member 19 is connected to the lower end of member 17 and comprises a casing formed of a helical member 19a having a plurality of rods 19b therein and spot welded thereto, member 19a having spaces between its convolutions. A solid pointed head 19c is connected to the lower end of screen 19.

Casing 14 extends upwardly into the block 12 and is connected to a passage 12a therein. Discharge pipe 16 extends to a block 20 communicating with a passage 20a, which in turn communicates with a larger passage so that a valve seat 20b is formed with which cooperates a valve 21 having a stem 21a extending through a closing and packing member 22 and provided with a handle 23 at its upper end. Member 22 is threaded into and secured into a top closing member 20c for block 20. Stem 21a is suitably threaded so that valve 21 is closed or opened by rotation of handle 23. A discharge pipe 24 extends from the side of block 20 and will convey the discharged oil to the desired place. A gauge 25 is connected with block 20 and communicates with passage 20a. A small pipe or conduit 26 is connected by a suitable coupling 27 to block 20 communicating with passage 20a and at its upper end is connected by a suitable coupling 28 to a valve block 30. Block 30 has a passage 30a at its lower end with which communicates a conduit 31 threaded into said block and to which air under pressure is delivered. Passage 30a communicates with a larger passage 30b forming therewith a valve seat 30c on which a valve 32 is adapted to seat, said valve having a valve stem 32a extending through suitable closing and packing means 33 secured in a top closing member 34 of block 30. Stem 32a is provided at its upper end with a handle 35 and is suitably threaded so that rotation of handle 35 opens and closes valve 32. A small passage 30d extends from passage 30b communicating with a larger passage 30e and forming therewith a valve seat with which cooperates a valve 36 equipped with a handle 37 extending through and suitably threaded in packing members 38. Passage 30e is connected by a small passage 30f to a passage with which communicates pipe 26. Another small passage 30g extends from passage 30b and communicates with a larger passage 30h forming therewith a valve seat with which cooperates a valve 39 having secured thereto a handle 40 extending through and suitably threaded in connecting and packing means 41 secured in block 39. A small exhaust passage 30i extends from passage 30h to the top of block 39 and thus to the atmosphere. Passage 30b is connected by conduit 44 to valve block 12. Block 12 has a passage 12a therein which is connected by suitable means, such as a conduit 46, to the casing 14. Conduit 44 communicates with a passage 12b in block 12 communicating at one end with passage 12a and adapted to be closed off therefrom by a valve 47 cooperating with a valve seat 12c and having a valve stem 47a extending through suitable connecting and packing members 48 threaded into and secured in the closing

member 49 for valve block 12. Valve rod 47a is equipped with a handle 50 and valve 47 can be opened and closed by rotation of handle 50. Passage 12b communicates with a passage 12d and is adapted to be shut off therefrom by a valve 52 cooperating with a valve seat 12e and having a stem 52a extending through and suitably threaded into connecting and packing means 53 threaded to and secured in a closing member 54 for block 12. Valve rod 52a is equipped with a handle 55 at its outer end and valve 52 can be opened or closed by rotation of handle 55. Passage 12d is adapted to be connected by suitable means such as a conduit 57 with the casing 11 and thus with the chamber 10b between the wall of well 10 and casing 14. Conduit 57 is provided with a branch conduit 58 connected to an exhaust valve 59 having a cock 59a which can be turned to open or close said valve and thus connect or shut off passage 12d from the atmosphere. Passage 12d also communicates with a passage 12f and is adapted to be shut off therefrom by a valve 62 arranged to cooperate with the seat 12 and equipped with a stem 62a extending through and suitably threaded to connecting and packing members 63 secured in a closing member 64 of block 12. Stem 62a has a handle 65 connected to its outer end and valve 62 can be closed or opened by rotation of handle 62. Passage 12f has connected thereto a conduit or pipe 66 threaded into a closing member 67 of block 12. Passage 12a communicates with an exhaust passage 12h extending to the outer side of block 12 and thus to the atmosphere and is adapted to be shut off from passage 12h by a valve 68 cooperating with a seat 12i and having a stem 68a extending through and suitably threaded in connecting and packing means 69 threaded in and secured in a closing member 70 of block 12. Stem 68a is provided with a handle 71 at its outer end and valve 68 can be opened and closed by rotation of handle 71.

A small passage 12j communicates with passage 12b beyond valve 47 and is controlled by a valve 72 having a stem 72a suitably supported and threaded into connecting and packing means 73 threaded in and secured in block 12. Stem 72a has a handle 74 at its outer end and rotation of handle 74 will open and close valve 72. A gauge 76 is connected to block 12 and communicates with passage 12j. A small passage 12m communicates with passage 12b beyond valve 52 and is controlled by a valve 77 having a stem 77a suitably threaded and supported in packing and connecting means 78 threaded in and secured to block 12. Stem 77a has a handle 79 at its outer end so that rotation of handle 78 will open and close valve 77. A gauge 80 is connected to block 12 and communicates with passage 12m.

In operation valve 32 will normally be closed. The oil in the well will pass from chamber 10b through the openings 14a into the casing 14. This oil will pass through the screen 19 lifting valve 18, and the level of oil will be substantially the same in chamber 10b, casing 14 and the discharge pipe 16. To determine the amount of oil in the well valve 21 will be closed and valve 32 will be opened. Valves 47 and 52 are closed. Valve 36 will be opened by turning handle 37. Air under pressure is now delivered into passage 30b, through passage 30c, through conduit 26 and to the discharge pipe 16. This air which is thus bled into pipe 16 will pass downward in said pipe forcing the oil down and will leak out when it gets down to openings 16b. The pressure thus

created in discharge pipe 16 will then equal the pressure of the head of oil in casing 14 and this pressure will show upon the gauge 25. If said gauge is calibrated in feet of water then the maximum pressure recorded on the gauge indicates the height of liquid in the casing 14, and since the size of the casing is known, the quantity of oil therein is readily known. This feature of the apparatus permits the operator to know accurately when sufficient oil has collected in casing 14 to justify flowing the well.

When the well is to be blown or discharged, valve 21 is opened to connect discharge pipe 16 to the flow or discharge conduit 24. Valve 36 will be closed and valve 32 will be opened. Valve 47 will be opened and valves 52 and 68 will be closed. Air under pressure is now delivered from the conduit 31 through passage 30b, conduit 44, passage 12b, past valve 67, into passage 12a and through conduit 46 to casing 14. The air now passes downwardly in casing 14 and the oil is forced downwardly and will be forced upwardly and out of pipe 16. When the air in casing 14 passes down to openings 16b, it will pass into discharge pipe 16 and force the oil still in said pipe upward and out through conduit 24. When the air is delivered to casing 14 the pressure will close valve 18. When air appears at the top of discharge pipe 16 or in flow pipe 24, valve 21 will be closed. The air under pressure will thus be retained in casing 14. After valve 21 is closed and valve 32 closed, valve 52 will be opened. This will permit the discharge of the air under pressure from casing 14 through conduit 46, passage 12a, past valve 47, into passage 12b, past valve 52, into passage 12d and through conduit 57 to casing 11. The air is thus exhausted from the top of casing 14 and delivered to the top of chamber 10b. This acts to force the oil in chamber 10b downwardly and the oil will pass through the openings 14a into casing 14, through and into the screen 19 and past valve 18 into discharge pipe 16. The casing 14 will thus be again filled to the same level as oil in the well and this level will also be in the discharge pipe 16. The quantity of compressed air in casing 14 in one installation and practice after valve 21 was closed was approximately 5 barrels at 500 pounds' pressure which is the pressure which has been used in practice. The capacity of the well was approximately 25 barrels. When the compressed air is discharged into the well or into chamber 12b, the air flows into chamber 10b until the pressure in the casing 14 dropped to approximately 100 pounds. After the air has been discharged into the well or chamber 10b, valve 68 is opened and the pressure remaining in casing 14 is discharged to the atmosphere through passage 12h. Then the 100 pounds' pressure in chamber 10b acts further to force the oil through screen 19, past valve 18 and into the casing 14 and discharge pipe 16. If the well is a low capacity well the oil forced into casing 14 and pipe 16 is allowed to remain therein for a day or two for a further collection. If, however, the well is a large producer it may be possible to again repeat the blowing operation as above described. The passage 12f and conduit 66 are provided for the discharge of gas from the well and this may be utilized for instance as a fuel for gas engines to operate the air compressors for producing a supply of compressed air or air under pressure. After the well has been blown, valve 32 will be closed, and as stated, valve 21 will be closed. Valves 47 and 52 will be closed and valve 62 will be opened. The gas from the

well can now pass from chamber 10b and casing 11, through conduit 57 to passage 12d, past valve 62 and out through passage 12f and conduit 66.

The passage 30i to the atmosphere is provided so that any leakage of high pressure air past valve 32 will be exhausted to the atmosphere. Valve 39 is thus opened during the periods between blowings. This exhausting of the leakage of air to the atmosphere eliminates the necessity of valves 47 and 52 being highly accurate for forming completely perfect closures. Exhausting the leakage of air through passage 30i thus prevents this air from reaching the gas discharged from the well and diluting the same. The smallest leak at 500 pounds will dilute the gas to such an extent as to stop the operation of the gas engine. Valve 59 is provided so that the pressure in the well or chamber 10b can be exhausted to the atmosphere when desired. The gauge 80 is provided so that an operator by opening valve 71 can determine the pressure in the well or in chamber 10b. The gauge 76 is provided so that the operator by opening valve 72 can determine the pressure in casing 14. In practice quite a number of wells are similarly connected to the air pressure line. The gauges 76 and 80 may be carried by an inspecting operator and placed in the valve block 12 at each well as he goes from one well to another. The valves 72 and 71 are thus necessary.

As above stated, the drawings illustrate an oil well which in practice had the casing 14 of about 4 inches' inside diameter and 300 feet long, the same having a capacity of approximately 4½ barrels.

Also, as stated in the description of the views, Fig. 1 is a schematic view, while Figs. 5 and 6 show the valve block 12 with the connections thereto as it is actually used in practice.

From the above description it will be seen that I have provided a simple and efficient method and apparatus for blowing oil wells. The wells are efficiently discharged and this is done by a comparatively small amount of compressed air. Certain objections which were present in the prior art are also eliminated. The method and apparatus have been amply demonstrated in actual practice, found to be very successful and efficient and the same have been successfully used on several hundred oil wells in the State of Pennsylvania.

It will of course be understood that various changes may be made in the form, details, arrangement and proportions of the apparatus and in the steps and sequence of steps of the method without departing from the scope of applicant's invention, which, generally stated, consists in a method and apparatus capable of carrying out the objects above set forth, such as disclosed and defined in the appended claims.

What is claimed is:

1. An apparatus for blowing an oil well having in combination, a casing disposed in said well and spaced from the wall thereof so as to form a chamber thereabout, said casing extending below the oil supply and having openings for the passage of oil thereinto, an oil discharge conduit extending downwardly into said casing to adjacent the bottom thereof having communication adjacent its lower end with said casing and adapted to receive oil adjacent its lower end, a second conduit for supplying air under pressure to said casing for discharging oil through said discharge conduit, means for closing said discharge conduit, and means for connecting said casing to said

chamber to discharge air under pressure thereinto for forcing oil into said casing.

2. The structure set forth in claim 1, a discharge conduit for gases, means for shutting off the supply of air under pressure to said casing and means for connecting said gas discharge conduit to said chamber.

3. An apparatus for blowing an oil well having in combination, a casing disposed in said well and spaced from the wall thereof so as to form a chamber thereabout, said casing extending below the oil supply and having openings for the passage of oil thereinto, an oil discharge conduit extending downwardly into said casing to adjacent the bottom thereof, said discharge conduit having an air discharge opening adjacent the bottom of said casing, a second conduit for supplying air under pressure to said conduit adjacent the top thereof, means for closing said discharge conduit adjacent the top of said casing whereby air can be forced downwardly into said discharge conduit to force oil therefrom down to said opening, and means for indicating the head of oil in said casing.

4. An apparatus for blowing an oil well having in combination, a casing disposed in said well and spaced from the wall thereof so as to form a chamber thereabout, said casing extending below the oil supply and having openings for the passage of oil thereinto, an oil discharge conduit extending downwardly into said casing to adjacent the bottom thereof and having an opening at its lower end, a second conduit for supplying air under pressure to said casing, means for closing said discharge conduit, a gauge in said discharge conduit, a member connected to said second conduit having a chamber therein, a passage extending from said chamber to said discharge conduit adjacent said gauge, a valve for controlling said passage, and a valve for shutting off and permitting communication between said last mentioned chamber and second conduit whereby the pressure in said discharge conduit and thus the amount of oil in said casing can be read upon said gauge.

5. In an oil well blowing apparatus including an oil-receiving casing in said well and a chamber about said casing, a block having a passage therein adapted to be connected to a source of air under pressure, a valve-controlled conduit connected to said passage, said block having a second passage for the discharge of gas from said chamber, a third passage adapted to be connected to said casing and a fourth passage adapted to be connected to said chamber, a valve in said block for shutting off or permitting communication between said first mentioned passage and said second and fourth passages, a second valve in said block for shutting off or permitting communication between said first mentioned passage and third passage, and a third valve in said block for shutting off or permitting communication between said second and fourth passages.

6. The structure set forth in claim 5, said block also having an exhaust passage extending to the atmosphere and a valve for shutting off or permitting communication between said third passage and said exhaust passage.

7. The structure set forth in claim 5, a conduit connected to said fourth passage and chamber and a valve for shutting off or permitting communication between said fourth passage and the atmosphere.

8. The structure set forth in claim 5, a small passage extending from said fourth passage, a

gauge connected to said small passage, and a valve controlling said small passage whereby when said last mentioned valve is open and said first mentioned conduit is closed and said third valve is closed said gauge will indicate the pressure in said chamber.

9. An apparatus for blowing an oil well having in combination, a casing disposed in said well and spaced from the wall thereof so as to form a chamber thereabout, said casing extending below the oil supply and having openings for the passage of oil thereinto, an oil discharge conduit extending downwardly into said casing to adjacent the bottom thereof, a second conduit for supplying air under pressure to said casing, means for closing said discharge conduit, a valve block having a passage therein to which said second conduit is connected, means for shutting off and permitting communication between said passage and second conduit, means connecting said casing and passage, and a gauge connected to said passage for indicating the pressure in said casing.

10. The structure set forth in claim 9, a small passage connecting said passage and gauge, and a valve for controlling said small passage.

11. In an oil well blowing apparatus including an oil-receiving casing in said well and a chamber about said casing, a block having a passage therein adapted to be connected to a source of air under pressure, a valve in said block for shutting off or permitting communication between said passage and casing, an exhaust passage in said block extending to the atmosphere, a valve for shutting off or permitting communication between said casing and exhaust passage, a second passage in said block connected to said chamber, and a valve in said block for shutting off or permitting communication between said second passage and first-mentioned passage.

12. The structure set forth in claim 11, a discharge passage for gas in said block, and a valve in said block for shutting off or permitting communication between said second passage and said discharge passage.

13. The structure set forth in claim 11, a small valve-controlled passage in said block connected to said first mentioned passage, and a gauge connected to said block and communicating with said small passage.

14. An apparatus for blowing an oil well having in combination, a casing disposed in said well and spaced from the wall thereof so as to form a chamber thereabout, said casing extending below the oil supply and having openings for the passage of oil thereinto, an oil discharge conduit extending downwardly into said casing to adjacent the bottom thereof, means for delivering air under pressure into said casing to discharge oil through said conduit, and means for closing said discharge conduit, a conduit including a portion of said first mentioned means connecting said casing to said chamber, a valve movable to closed position for closing said last mentioned conduit to retain said air under pressure in said casing and movable to open position to open said conduit and permit said air under pressure to pass into said chamber for forcing oil from said chamber into said casing.

15. An apparatus for blowing an oil well having in combination, a casing disposed in said well and spaced from the wall thereof so as to form a chamber thereabout, said casing extending below the oil supply and having openings for the passage of oil thereinto, an oil discharge conduit

extending downwardly into said casing to adjacent the bottom thereof, a second conduit for supplying air under pressure into said casing, a third conduit extending to said casing and to said second conduit, a valve adapted to be opened for connecting said second and third conduits and to be closed to cut off communication between the same, a fourth conduit connected to said chamber and extending to said third conduit, a second valve adapted to be closed for shutting off communication between said third and fourth conduits and adapted to be opened for connecting said third and fourth conduits, and a third valve for closing said second conduit whereby by opening said first mentioned and third valves and closing said second valve, air under pressure can

be delivered to said casing to force oil through said discharge conduit, and by closing said third mentioned valve and opening said first and second valve, said air from said casing can be delivered to said chamber to force oil into said casing.
